Patented Apr. 25, 1922.

UNITED STATES PATENT OFFICE.

WILLIAM C. WRIGHT AND THOMAS I. DEAN, OF BUFFALO, NEW YORK.

MUSIC-ROLL CABINET.

1,414,317.

Specification of Letters Patent. Patented Apr. 25, 1922.

Application filed August 10, 1920. Serial No. 402,651.

To all whom it may concern:

Be it known that we, WILLIAM C. WRIGHT, a citizen of the United States, and THOMAS I. DEAN, a subject of the King of England, residing at Buffalo, in the county of Erie and State of New York, have invented new and useful Improvements in Music-Roll Cabinets, of which the following is a specification.

10 This invention relates to a holder or cabinet for filing music rolls such as are used for player-pianos.

One of the objects of the invention is to provide a holder of this character which 15 is simple in construction, which is not liable to get out of order and which can be manufactured at a moderate cost.

A further object is to provide means for 20 ejecting or moving the rolls to a position in which they can be conveniently grasped by the user and readily removed from their compartment or holder.

A still further object of the invention is to provide means for protecting the music 25 rolls against moisture and injury while in the holder.

In the accompanying drawings:

Figure 1 is a perspective view of one 30 form of holder embodying our improvements. Figure 2 is an enlarged fragmentary longitudinal section thereof on line 2-2, Fig. 1. Figure 3 is a fragmentary transverse section on line 3-3, Fig. 1. Figure 4 is a fragmentary top plan view thereof, 35 partly in section. Figure 5 is a front elevation of a modified form of music roll holder.

Similar characters of reference indicate corresponding parts in the several views.

40 Referring to Figs. 1-4, the invention is shown as applied to a piano bench 10, wherein the case or body 11 is made of the proper depth to serve as a holder or receptacle for the music rolls. The top of the case is provided with a hinged lid 12 which acts not only as a closure for the holder but also forms the seat of the bench.

The case 11 of the bench is provided with a plurality of individual compartments or 50 pockets 13 open at their outer or upper ends for the reception of the music rolls 14, the latter having the customary flanged ends 15 and journals 16. These compartments are preferably in the form of tubes constructed of card board or similar material 55 and are disposed vertically in the body 11.

The diameter of these tubes is somewhat greater than the diameter of the music rolls, and they are of a height substantially equal to the length of the rolls, thereby enclosing 60 the latter throughout their length and protecting them against moisture and against contact with other rolls. These tubes may be secured to the body in any suitable manner, for instance, by providing annular 65 grooves 17 in the bottom 18 thereof and gluing or otherwise fastening the tubes therein.

As shown in Fig. 1, these tubes are preferably arranged in parallel rows which extend transversely of the case 11.

Arranged centrally in the lower end of each compartment 13 is an ejecting device which preferably comprises a supporting base or bearing cup 19 yieldingly mounted 75 on a coil spring 20, one end of which is suitably fastened to the underside of said base while the other end is seated in a socket 21 in the bottom 18 of the body 11 and rigidly secured therein. The upper side of this base is provided with a recess or seat 22 which is adapted to receive the inner or lower journal 16 of the music roll.

Slidable in the upper end of the holder, transversely of the rolls, is a plurality of 80 rows of retaining or head-plates 23 corresponding in number to the compartments 13 and co-operating with the supporting bases 19 to hold the music rolls in position within their compartments. The plates of each row are guided at their opposite longitudinal edges in horizontal ways 24 provided in the upper side of fixed rails 25 extending across the upper portion of the case 11.

Strips 26 suitably secured to the upper edges 85 of these rails prevent vertical displacement of said retaining plates. Depending from the underside of each of the latter is a bearing or cup 27 having a seat 28 which is adapted to receive the adjacent upper or outer journal 16 of the music roll. Thus, the latter is normally held between the yieldable base or bearing 19 at its lower end and the laterally slidable bearing 27 at its upper end, the coil spring 20 being under 100 compression and tending to elevate and project the roll from the case 11.

When it is desired to remove a music roll from the holder, the user depresses the roll sufficiently with one hand to release its 110 upper journal 16 from the upper bearing-cup 27, and then slides the corresponding

plate 23 to one side with the other hand, far enough to clear that end of the roll, thus permitting the spring to eject or elevate the roll to the position shown by full lines in 5 Figs. 3 and 4 of the drawings, and enabling the same to be conveniently grasped to completely remove it from the holder. The sliding movement of each retaining plate is limited in both directions by stops 29 properly arranged in the guideways 24, to pre- 10 determine the roll-holding and releasing positions.

As clearly shown in Fig. 4, the side edges of the slides or plates 23 are preferably 15 formed with curved or concave recesses 30, to enable the rolls to be freely inserted and removed, and also to permit the user to conveniently depress the roll prior to ejecting the same from its compartment.

20 If desired, the retaining plates 23 may be provided with operating buttons 31 bearing numerals or other indicia corresponding to the numbers given the music rolls in the index usually kept for such purposes.

25 From the foregoing it will be noted that this improved holder is exceedingly simple in construction, reliable in operation, and permits ready removal and replacement of the music rolls while at the same time protecting them against injury.

30 In the modification shown in Fig. 5, our improvement is shown as applied to a cabinet 32 open at its front side and provided with horizontally-swinging doors 33. The construction of the music roll compartments and 35 ejecting means are identical to those previously described in the piano bench form, except that the rolls are arranged horizontally instead of vertically.

40 Both forms of holders here shown present a neat appearance, making them a very attractive and useful piece of furniture for the home.

We claim as our invention:

45 1. A music roll holder, comprising a case for containing music rolls, individual compartments for said rolls open at their front ends, means in said compartments for ejecting the music rolls therefrom, and means

slidable across the open ends of said compartments for normally retaining the rolls therein.

2. A music roll holder comprising a case for containing music rolls, bearing members for one end of said rolls, movable bearing members for the other ends of the rolls, the last-named bearing members being laterally movable to release the rolls, and means for ejecting the rolls from said case when released from said movable bearing members.

3. A music roll holder comprising a plurality of compartments for receiving music rolls, a yieldable roll-bearing arranged at one end of each compartment, and a laterally-slidable retaining plate arranged at the other end thereof and having a roll-bearing, said yieldable bearing tending to force the music roll toward said retaining plate.

4. A music roll holder comprising a plurality of compartments for receiving music rolls, a roll-ejecting device arranged at one end of each compartment, a slidale roll-retaining member at the other end thereof, means for guiding said member, and stops for limiting the movement of said retaining member.

5. A music roll holder comprising a case, a plurality of tubular compartments arranged in said case and open at their outer ends for receiving the music rolls, roll-ejecting devices arranged at the inner ends of said compartments, respectively, and slideable bearing-plates movable across the open ends of the compartments, said ejecting devices and bearing plates adapted to normally support the music rolls in said compartments.

6. A music roll holder comprising a case for containing music rolls, bearing members for one end of said rolls, laterally-movable slides having bearings for the other ends of the rolls, said slides being provided in their side edges with recesses, and means for ejecting the rolls from said case when said slides are moved aside.

WILLIAM C. WRIGHT.
THOMAS I. DEAN.
